UNITED STATES PATENT OFFICE

2,606,491

TYPE BAR

William Wockenfuss, Union, N. J., assignor, by
mesne assignments, to Burroughs Adding Ma-
chine Company, a corporation of Michigan

Application October 16, 1948, Serial No. 54,933

7 Claims. (Cl. 101—109)

1

This invention relates to improvements in printing devices and has particular reference to a type bar construction such as used on record controlled tabulating machines and the like.

An object of the invention is to facilitate the mounting and replacement of type elements in a container by providing the body of the latter with a removable cover member and forming on said container and member coacting means which interengage to securely retain the cover member in operative position and which also permit of said cover member being readily removed to gain access to said type elements.

Another object is to provide an improved printing device wherein a type container which is removably mounted upon a type bar is securely held thereon, against accidental displacement, by a locking element which coacts with portions of said container and bar to releasably connect the same together in such manner as to enable the container to be readily removed from the bar when repairs to or replacement of said container and the type elements therein are necessary.

Another object is to provide the type container with means which cooperate with a removable cover to secure the latter in retaining position relative to a locking element that joins the container to a type bar.

The inventive idea involved is capable of receiving a variety of mechanical expressions, one of which, for purposes of illustration, is shown in the accompanying drawing; but it will be expressly understood that said drawing is merely used for the purpose of illustrating the invention as a whole and not to define the limits thereof, reference being had to the appended claims for this purpose.

In the drawing:

Fig. 1 is a fragmentary side elevation, partly broken away, of a printing device constructed in accordance with the invention;

Fig. 2 is a section taken on the line 2—2 of Fig. 1;

Fig. 3 is a transverse section on the line 3—3 of Fig. 1;

Fig. 4 is a fragmentary perspective view of the body of the container in which the type elements are mounted;

Fig. 5 is a similar view of the removable cover member for said body;

Fig. 6 is a perspective view of a locking element employed to releasably connect the type container to a type bar; and

Fig. 7 is a fragmentary perspective view of the type bar.

2

In accordance with one of the features of the present invention, the upper end of the type bar 8 is provided with a bifurcation 9 enlarged transversely at its inner end to form locking shoulders 10, and further enlarged at its outer end to provide stop shoulders 11, the purposes of which will appear in the course of the description.

The body of the type container, generally indicated at 12, which is removably mounted upon the type bar 8 is stamped or otherwise formed from a single sheet of material to provide the back 13 having side walls 14 extending along the longitudinal edges thereof. At the lower end of the body and at an intermediate portion thereof the side walls have extending inwardly therefrom two pairs of flanges 15 and 16 spaced apart and constituting permanent and partial closure for said body, and in the space between said pairs of flanges and spaced therefrom is a pair of opposed inturned lugs 17 forming retaining elements, the purpose of which will later appear. At a point adjacent the lower end of the back 13 of the container body a guide 18 is struck therefrom which engages in the bifurcation of the type bar as the container is being mounted thereon to guide the latter into proper position on the bar. At an intermediate point of the back 12 directly beneath the flanges 16, said back also has struck therefrom a substantially circular projection or boss 19 which, when the container is properly disposed upon the type bar, will be contacted by the stop shoulders 11 of said bar to limit the movement of the container to its proper position. Said boss 19 is provided therein with an opening 20 in alignment with the bifurcation 9 in the type bar for a purpose which will appear in the course of the description. The upper portion of the container body 12 is open faced and the parts of the side walls 14 extending along said portion are provided with pairs of re-entrant slots 21 in which the type elements 22 of well known construction are adapted to be removably mounted, each of said elements being provided with a recoil spring 23 for restoring the element to its normal position shown in Fig. 1 after it has been operated to print a character in a manner well known in the tabulating art.

The invention further provides a device for releasably interconnecting the type container with the type bar in a manner which will prevent accidental detachment of said container during operation of the tabulating machine, and particularly when the type bars are arrested in their printing position which operation is usually accomplished by engagement of a pawl with a tooth

on the type bar. Preferably, said device is in the form of an elongated locking element 24 (Fig. 6) formed from a strip of resilient material provided at one end with an anchoring head 25 and at its opposite end with a locking head 26. Said locking element is freely mounted in its operative position and retained therein by the cover member or plate 27 (Fig. 5) in a manner to be described. When in operative position the anchoring head 25 is seated in the boss 19 of the container and its shank extends from said boss through the opening 20 therein with the upper portion of the element 24 disposed within the upper end of the bifurcation 9 when the container is mounted on the type bar, and the remaining portion of said element 24 being in alignment with said bifurcation and slightly bowed so as to rest upon the guide 18 at the lower end of the container body, as best illustrated in Fig. 2. Due to this biased said condition of said element 24, it will be apparent that when the container is mounted upon the type bar with the boss 19 in engagement with the shoulders 11 of said bar, the inner edges of the offset locking head 26 will engage the shoulders 10 at the inner end of the bifurcation 9 in the type bar and will thus securely lock the container thereon. A lip 28 at the free extremity of the head 26 is provided in order that the element 24 may be flexed outwardly against its normal tendency to remain in locking position, to disengage the locking head from the shoulders preliminary to detaching the container from the type bar.

After the locking element 24 has been so positioned the cover plate 27 is mounted in place to retain said element 24 in such position and to close the upper open faced portion of the container body in which the type elements 22 are disposed. In mounting the cover member on the body, the flanged and offset lower portion 29 thereof is first inserted over the cover sections 16 and then under the inturned lugs 17, as indicated in dotted lines in Fig. 4. This will dispose the cover member at a slight angle to the body of the container with the closure flange 30 at the upper end of said cover extending slightly beyond the upper end of the body 12. Inward pressure is then exerted upon the upper end of the cover to flex the same to a position wherein the intermediate portion of the cover will engage the free edges of the side walls 14 of the body, and then downward pressure is applied to said cover to force the lower portion 29 completely under the retaining lugs 17 so that the flange 31 at the lower extremity of the cover will engage behind said lugs and thus lock the cover against a reverse or upward movement. The closure flange 30 at the upper end of the cover is provided at its ends with notches 32 which receive lugs 33 formed at the upper ends of the side walls 14 of the body when said cover is in the last described position, and the interengagement of said closure 30 with the lugs 33 will retain the cover member, in its slightly flexed condition, against the side walls 14 so as to fully enclose the type elements 22. With the cover member in its operative position it will be apparent from Fig. 2 that the lower offset portion 29 thereof will engage the shank of the locking element 24 and prevent it from becoming displaced from its operative position in alignment with the bifurcation 9 in the type bar, and will also exert sufficient inward pressure upon said element to retain the locking head 26 in engagement with the shoulders 10 until said locking head is forcibly sprung out-

wardly preliminary to removing the container from the type bar. The upper edge of the back 13 of the container body is provided with a notch 34 for the insertion of a tool utilized to spring the closure 30 out of engagement with the lugs 33 when it is desired to remove the cover member from the container.

What is claimed is:

1. A printing device comprising a type bar having a bifurcation at one end formed with locking shoulders, a type container removably mounted on the bifurcated end of said type bar, and a separate locking element for connecting said container and type bar and freely removable therefrom, said element having one end interengageable with said container and its other end with said type bar, the latter end provided with a locking head releasably engaged with the shoulders formed on said type bar.

2. A printing device comprising a type bar having a bifurcation at one end formed with locking shoulders, a type container removably mounted on the bifurcated end of said type bar and having a boss formed thereon providing a recess, and a locking element having an anchoring head at one end disposed in the recess of said boss with an intermediate portion of said element extending in alignment with said bifurcation and provided at its opposite end with a locking head releasably engaging said shoulders.

3. A printing device comprising a type bar having a bifurcation at one end formed with locking shoulders, a type container removably mounted on the bifurcated end of said type bar, a locking element freely carried by said container with a portion thereof disposed in said bifurcation when said container is mounted on said bar, said locking element provided with a locking head releasably engaged with said shoulders, and a removable cover for said container having a portion engaging said locking element to retain the same against displacement with respect to said type bar and container while said cover is in operative position.

4. A printing device comprising a type bar having a bifurcated portion formed at its outer and inner ends, respectively, with stop and locking shoulders, a type container into which said bifurcated portion is insertable and having a boss engageable by said stop shoulders, an elongated resilient locking element having an anchoring head at one end seated in said boss and a locking head at its other end engaging said locking shoulders and releasable therefrom by flexing said locking head, and means to retain said locking element in operative position.

5. A printing device comprising a type bar having a bifurcated portion formed at its outer and inner ends, respectively, with stop and locking shoulders, a type container into which said bifurcated portion is insertable and having a boss engageable by said stop shoulders, an elongated resilient locking element having an anchoring head at one end seated in said boss and a locking head at its other end engaging said locking shoulders and releasable therefrom by flexing said locking head, and a removable cover member engaging said locking element to retain the same in operative position, said cover member and container having coating means for removably holding said member in covering position on the container.

6. A printing device comprising a type bar bifurcated at one end and having locking shoulders formed in the bifurcation, a type container

removably mounted on the bifurcated end of said type bar and comprising a body having spaced cover retaining means, a locking element having one end anchored in said body and its other end provided with a locking head engaged with the shoulders formed on said type bar, and a cover member for said body engaging said locking element and having portions thereof coacting with the retaining means on said body to hold the head on said locking member in engagement with said shoulders.

7. A printing device comprising a type bar bifurcated at one end and formed in said end with locking shoulders, a type container removably mounted on the bifurcated end of said type bar and comprising a body having anchoring means formed in a wall thereof and further having side walls provided with spaced cover section and retaining means intermediate the ends thereof, a locking element having a portion engaging said anchoring means and further having a locking head engaging the shoulders in the bifurcation of said type bar, a cover for said body having portions overlying said cover section and underlying said retaining means with one of said por-

tions engaging said locking element to retain the same in locking position, and cooperating means between said body and cover for retaining the latter in operative position.
